CLAIM

(80) **Hague Agreement Data**

The ornamental design for a nail vacuum cleaner for manicure and pedicure, as shown and described.

Int. Filing Date: **Mar. 20, 2020**

DESCRIPTION

Int. Reg. No.: **DM/209436**

1. Nail vacuum cleaner for manicure and pedicure

Int. Reg. Date: **Mar. 20, 2020**

1.1 : Perspective front left

Int. Reg. Pub. Date: **Jul. 31, 2020**

1.2 : Perspective front right
